TENDON PULLER

Ralph S. Zebarth, Hickman Mills, Mo., assignor to Gordon Johnson Equipment Company, Kansas City, Mo., a corporation of Missouri

Application June 8, 1954, Serial No. 435,204

4 Claims. (Cl. 17—11.3)

This invention relates to equipment adapted for use in the process of dressing poultry and particularly to a tendon puller capable of breaking turkey legs and removing the tendons in a single operation.

It is the most important object of the present invention to provide a machine for quickly and efficiently breaking turkey legs as quickly as the same are inserted into slots provided in the machine therefor, and to slowly and steadily pull the tendons so that the same are removed without breaking.

Another important object of the instant invention is to provide a tendon puller that is fast in its operation so that the turkeys may be removed from a conveyor line, the legs inserted for breaking and removal of the tendons in the machine and the turkey replaced on the conveyor line as the latter continues to move alongside the tendon pulling machine.

Other important objects include the way in which slotted brackets are provided and disposed relative to a breaking bar or anvil so as to hold the legs against tipping as the same are broken and as the tendons are pulled therefrom; the way in which a slotted, rotatable member is disposed to move past slotted brackets to receive the legs and impart a gradual pull thereon; and the manner of providing automatic ejecting means for removing the legs from the slots of the rotating member after the legs are broken and the tendons removed.

In the drawings:

Figure 1 is a front perspective view of a tendon puller made pursuant to the instant invention.

Fig. 2 is an enlarged, top plan view thereof with the cover removed.

Fig. 3 is a fragmentary, cross-sectional view taken on line III—III of Fig. 2.

Fig. 4 is a view similar to Fig. 3 taken on line IV—IV of Fig. 2; and

Fig. 5 is an enlarged fragmentary, cross-sectional view taken on irregular line V—V of Fig. 3.

A hollow, open top housing 10 is shown in the drawings mounted on suitable framework 12, the latter of which also mounts and supports a rotor broadly designated by the numeral 14 through the medium of bearings 16 receiving horizontal shaft 18 of the rotor 14.

Frame 12, together with brackets 20 thereon, supports a shelf or platform 22 upon which is secured an electric motor or other prime mover 24 coupled by belt and pulley means 26 with a gear reduction unit 28 also carried by the platform 22. An idler shaft 30 rotatably mounted on the platform 22 in parallelism with the shaft 18 is driven by chain and sprocket wheel means 32 operably interconnecting unit 28 and shaft 30. A pair of chain and sprocket wheel means 34 and 36 operably interconnect shafts 18 and 30.

In addition to the shaft 18, rotor 14 includes a pair of end discs 38 and 40 rigid to the shaft 18 and interconnected by a plurality of supporting bars 42 for combination hammer and pulling members 44. The transversely arcuate members 44 which span the distance between

2

the discs 38 and 40 are rigid to the bars 42 and are provided with a series of substantially V-shaped notches 46.

Rotor 14 is rotated anti-clockwise, viewing Fig. 3, past an elongated bar or anvil 48 secured to the frame 12 and having a horizontal, uppermost edge 50 at the front of the machine and along the top edge of housing 10. The anvil 48 supports a number of arcuate bracket elements 52 having opposed leg-receiving clearance notches 54.

Leg ejecting mechanism is provided for each member 44 respectively and including a rod 56 therebehind and rotatably supported by the discs 38 and 40 in parallelism with the shaft 18. An ejecting finger 58 extends into each slot 46 respectively, the fingers 58 being mounted on the rod 56 and being yieldably biased into the apexes of the slots 46 by spring 60. Spring 60 is connected at one end thereof to a pin 62 extending outwardly from disc 38 and at its opposite end to a small plate 64 secured rigidly to rod 56. Frame 12 mounts a trip bar 66 within the path of travel of the plates 64.

Cover 68 is provided with an access opening 70 at the front of the machine.

In operation, the rotor 14 is driven at a relatively low rate of speed by the prime mover 24 through the reduction unit 28. In order to break turkey legs and effectively, but quickly, remove the tendons, it is but necessary for the operator to place the legs in the V-shaped slots 54 with the knees disposed at the outermost faces of the bracket elements 52.

Those portions of the turkey legs to be broken and removed will, therefore, extend across the horizontal edge 50 of anvil 48 within the path of travel of the members 44 of rotor 14. Manifestly, the slots 54 are aligned with a pair of notches 46 of the members 44 and, therefore, as the members 44 move past the anvil 48 as best visualized from viewing Figs. 3 and 4, the legs which are protruding inwardly will be received in the notches 46 and the feet of the bird will be entirely confined within the rotor 14.

As the rotor 14 continues to rotate and as a member 44 grasping a pair of turkey legs within the notches 46, moves downwardly, the bracket 52 being used will hold the legs against tipping on the edge 50 of anvil 48 and, therefore, the said legs will be immediately broken.

The broken portions of the legs will thereupon be pulled downwardly and inwardly and by virtue of such gradual and steady pull, the tendons will not be broken but will be pulled out of the turkey legs and into the housing 10.

As soon as the plates 64 move to a position engaging the trip bar 66, as shown in Figs. 3 and 4 of the drawings, plates 64 will be swung anti-clockwise viewing Fig. 3, 50 with respect to the rotating rotor 14 and against the action of spring 60 to thereby swing the fingers 58 outwardly away from the apexes of notches 46 as shown in Fig. 4. The fingers 58, therefore, eject the legs from the members 44 and into the confines of the housing 10 for gravitation 55 to the floor where they may be subsequently collected and disposed of.

It is now apparent that all of the aims and objects of the instant invention initially set forth are attained through use of the structure just above described and, 60 therefore, while details of construction may be varied, it is desired to be limited only by the scope of the appended claims.

Having thus described the invention what is claimed as new and desired to be secured by Letters Patent is:

65 1. A combination leg-breaking and tendon-pulling machine for poultry comprising a rotor; a stationary anvil adjacent the circumference of the rotor, having a single edge parallel with the axis of rotation of said rotor across which both of the poultry legs are adapted to be laid in relative parallelism, and extending radially of the rotor thereinto toward said axis of rotation, with the feet of the poultry disposed on one side of the anvil and with the

knee joints thereof disposed on the opposite side of the anvil, said rotor being provided with a combination hammer and pulling member at said circumference thereof having a pair of notches disposed to receive said legs between the anvil and the feet when the legs are laid on the anvil and the rotor is rotated to move the member in one direction past the anvil; and retainer means for holding the legs against tipping on the anvil when received in said notches, whereby the member breaks the legs, including a bracket element mounted on said opposite side of the anvil, said element having a pair of leg-receiving notches, whereby the tendons are pulled by the member after breakage of the legs as the knee joints engage the element and the member engages said feet, each pair of notches being disposed in a line parallel with said axis of rotation and said edge.

2. A machine of the kind set forth in claim 1 wherein each notch of said member is provided with a shiftable leg ejector and wherein is provided trip means for shifting the ejector after pulling of the tendons.

3. A machine of the kind set forth in claim 1 wherein each notch of said member has leg-ejector means swingable on an axis parallel with said axis of the rotor, and wherein is provided stationary trip means within the path of travel of the ejector means for swinging the same.

4. A combination leg-breaking and tendon-pulling machine for poultry comprising a rotor having a pair of spaced ends; means mounting said rotor for rotation on a horizontal axis; a stationary anvil adjacent the circumference of the rotor having a single, uppermost, horizontal edge parallel with said axis across which both of the poultry legs are adapted to be laid in the same horizontal plane, in relative parallelism, and extending radial-

ly of the rotor thereinto toward said axis of rotation, with the feet of the poultry disposed on one side of the anvil and with the knee joints thereof disposed on the opposite side of the anvil, said rotor being provided with a plurality of spaced, elongated combination hammer and pulling members at said circumference thereof interconnecting said ends, each provided with a longitudinal row of notches disposed in parallelism with said axis for receiving said legs between the anvil and the feet when the legs are laid on the anvil and the rotor is rotated to move the members in one direction past the anvil; and retainer means for holding the legs against tipping on the anvil when received in said notches whereby the member breaks the legs, including a plurality of spaced bracket elements mounted on said opposite side of the anvil, each having a pair of oppositely-facing, leg-receiving notches aligned with a corresponding pair of notches of each member, whereby the tendons are pulled by the member after breakage of the legs as the knee joints engage the elements and the members engage said feet.
